Fig. 5.

FIGURE 1 is an isometric view of a case for beverage containers showing our new design;

FIGURE 2 is a top plan view thereof;

FIGURE 3 is a bottom plan view thereof;

FIGURE 4 is a modified view of the case of FIGURE 1 wherein stand-off ribs are provided on the inside walls thereof; and

FIGURE 5 is a top plan view thereof.

The sides and ends opposite the sides and ends shown in FIGURES 1 and 4 are identical.

This application is a continuation of our copending applications Ser. Nos. D.88,049 and D.88,051, both filed Nov. 9, 1965, both now abandoned.

We claim:

The ornamental design for a case for beverage containers, substantially as shown and described.
